US0D1043515S

(12) **United States Design Patent** (10) Patent No.: **US D1,043,515 S**
(45) Date of Patent: ** Sep. 24, 2024

(54) **VEHICLE WHEEL RIM**

(71) Applicant: **Mercedes-Benz Group AG**, Stuttgart (DE)

(72) Inventors: **Achim-Dietrich Badstübner**, Stuttgart (DE); **Robert Lesnik**, Stuttgart (DE); **Hanne Ruoff**, Stuttgart (DE); **Daniel Schumacher**, Stuttgart (DE); **Thomas Sälzle**, Stuttgart (DE); **Gorden Wagener**, Stuttgart (DE)

(**) Term: **15 Years**

(21) Appl. No.: **35/519,641**

(22) Filed: **Jan. 10, 2023**

(80) **Hague Agreement Data**

Int. Filing Date: **Jan. 10, 2023**

Int. Reg. No.: **DM/226423**

Int. Reg. Date: **Jan. 10, 2023**

Int. Reg. Pub. Date: **Jan. 12, 2024**

(30) **Foreign Application Priority Data**

Jul. 12, 2022 (DE) 402022201582.1

(51) **LOC (14) Cl.** **12-16**

(52) **U.S. Cl.**

USPC **D12/209**

(58) **Field of Classification Search**

USPC D12/204-213, 501; D21/563, 779
